(57) **CLAIM**

The ornamental design for a lunch box, as shown and described.

DESCRIPTION

1. Lunch box

FIG. 1.1 is an isometric front view of the design.

FIG. 1.2 is another isometric rear side view of the design.

FIG. 1.3 is a front view of the design.

FIG. 1.4 is a back view of the design.

FIG. 1.5 is a top view of the design.

FIG. 1.6 is a bottom view of the design.

FIG. 1.7 is a right side view of the design.

FIG. 1.8 is a left side view of the design.

1 Claim, 8 Drawing Sheets(56)
